J. F. MILLER & C. J. LOCKE.
AUTOMOBILE SIGNAL LIGHT.
APPLICATION FILED JAN. 30, 1915.

1,146,588.

Patented July 13, 1915.

UNITED STATES PATENT OFFICE.

JOSEPH F. MILLER AND CHARLES J. LOCKE, OF DETROIT, MICHIGAN.

AUTOMOBILE SIGNAL-LIGHT.

1,146,588.

Specification of Letters Patent.

Patented July 13, 1915.

Application filed January 30, 1915. Serial No. 5,179.

To all whom it may concern:

Be it known that we, JOSEPH F. MILLER and CHARLES J. LOCKE, citizens of the United States of America, residing at Detroit, in the county of Wayne and State of Michigan, have invented certain new and useful Improvements in Automobile Signal-Lights, of which the following is a specification, reference being had therein to the accompanying drawings.

This invention relates to an automobile traffic signal, and the principal object of our invention is to provide a signal which will indicate by day, as well as by night, to on-coming vehicles, the fact that the signal carrying vehicle is about to stop, reduce speed or turn into another lane of travel.

Another object of our invention is to provide a novel signal that is automatically actuated when a brake lever, clutch pedal, or other part of a vehicle is actuated thereby relieving the operator or chauffeur of the vehicle of the responsibility of operating the signal.

In attaining the above and other objects, the parts of the signal are constructed with a view to reducing the cost of manufacture and at the same time retain the features by which safety, durability, simplicity, and ease of assembling are secured, and with such ends in view, our invention resides in the novel construction, combination and arrangement of parts to be hereinafter specifically described and then claimed.

Reference will now be had to the drawing, wherein—

Figure 1 is a side elevation of a portion of a vehicle provided with the signal, illustrating one manner of automatically controlling the operation of the signal; Fig. 2 is an elevation of the signal as displaying the word "stop"; Fig. 3 is a longitudinal vertical sectional view of a portion of a signal; Fig. 4 is a cross sectional view of the signal, and Fig. 5 is a horizontal sectional view of a portion of the signal.

The signal comprises an oblong rectangular casing having a bottom plate 1, a rear wall 2, a front wall 3, end walls 4 and 5, a top plate 6 and a transverse partition 7, said partition dividing the casing into a large compartment 8 adapted to contain electrically actuated signal mechanism, and a small compartment 9 that accommodates a tail light or lamp; the front wall 3 of said

compartment having a conventional red bull's eye 10.

The front wall 3 of the compartment 8 is provided with an oblong sight or display opening 11 and connected to the bottom plate 1, contiguous to said opening, is a vertical apertured plate 12, said plate having the apertures or openings thereof representing characters, for instance the characters of the word "stop."

Movable in front of the apertured plate 12 is a vertically disposed shutter 14 preferably made of sheet metal. This shutter is slidable between the front wall 3 of the casing and vertical angle bars 15 secured to the partition 7 and the end wall 4 of the casing. The ends of the shutter 14 are cut and stamped out to provide rearwardly extending and vertically disposed racks 16 engaged by segment gears 17 on the ends of arms 18 mounted upon a longitudinal shaft 19, journaled in the end wall 4 and the partition 7 of the casing. The shaft 19 serves functionally as a rock shaft and the rear ends of the arms 18 are connected by a longitudinal rod 20 in parallelism with the shaft 19. Loosely connected to the rod 20 by a link 21 is a twisted extension 22 of an armature 23, said armature being associated with a conventional form of electromagnet 24 mounted upon a plate 25 secured to the rear wall 2 of the casing within the compartment 8. The electromagnet 24 is in circuit with a suitable source of electrical energy, as battery cells 26 and the circuit is controlled by a stationary contact 27 and a movable contact 28. The movable contact 28 can be supported by a clutch pedal 29 or other movable controlling device of a vehicle, such as an automobile. The signal can be attached to the frame or other support at the rear end of the vehicle and upon the operator throwing out the clutch or applying the brakes, an electrical circuit is established that energizes the electromagnet 24, attracts the armature 23 and through the medium of the elements 20 to 22 inclusive the shaft 19 is rocked to elevate the shutter 14 and displaying the characters of the apertured plate 12.

In order that the signal can be used at night, an incandescent lamp 30 is arranged within the compartment 8 to cast rays of light through the apertures or openings of the plate 12, and the bottom plate 1 of the casing has provision for sup-

porting and illuminating a license card 31. The license card 31 is suspended from a rod 32 carried by depending brackets 33 secured to the bottom plate 1. A reflector 34 containing an incandescent lamp 35 is arranged to cast rays of light upon the license card.

While in the drawings, there is illustrated a preferred embodiment of our invention it is to be understood that the structural elements are susceptible to such variations and modifications as fall within the scope of the appended claim.

What we claim is:—

In an automobile traffic signal, a casing 16 adapted for attachment to a vehicle, said casing having the wall thereof provided with an opening, an apertured plate in said casing adjacent to the opening thereof, a

shutter movable in front of said apertured plate and having the ends thereof bent and 20 formed to provide racks, a rock shaft longitudinally of said casing, segment gears carried by said rock shaft and engaging the racks of said shutter to move said shutter, an incandescent lamp in said casing, a rod 25 connecting said sector gears, a link connected to said rod, and electrically actuated means within said casing connected to said link and adapted for rocking said shaft.

In testimony whereof we affix our signatures in presence of two witnesses.

JOSEPH F. MILLER.
CHARLES J. LOCKE.
